COFFEE-MAKING APPARATUS

This invention relates to a coffee-making apparatus comprising an electric throughflow heater, connected to a water reservoir, for passing hot water to a filter.

Apparatuses of this kind, which are known in various embodiments, are provided with a mechanism for switching the throughflow heater on and off. As far as these switch mechanisms are arranged to control the apparatus automatically and in dependence on the presence of water, they have hitherto been of a highly vulnerable and unreliable operating construction.

It is an object of the present invention to provide a coffee-making apparatus having a switch mechanism which is free of the drawbacks referred to.

According to the invention, there is provided a coffee-making apparatus comprising an electric throughflow heater, connected to a water reservoir, for passing hot water to a filter, characterized in that, in the path of flow of the water to be heated, there is included a chamber having a float swiveling about a fixed point and a mercury switch for the throughflow heater, stationarily mounted in said float. In a preferred embodiment of the invention said float chamber is disposed immediately subjacent to the water reservoir.

One embodiment of the invention will now be described, by way of example, with reference to the accompanying, in which:

FIG. 1 is a vertical longitudinal section of the coffee-making apparatus according to the invention;

FIG. 2 is a plan view of the water reservoir; and

FIG. 3 and 4 show vertical longitudinal sections of the float chamber with the float in different positions.

Referring to the drawings, there is shown a coffee-making apparatus comprising a baseplate 1 including a heating plate 2 for a filtrate pot 3 which carries a removable filter 4.

Secured to the base plate 1 is a housing 5 carrying a water reservoir 6. The bottom of the reservoir 6 has a central column 7 and an eccentric recessed portion forming a float chamber 8. The float chamber 8 is roofed by a hood 11, the latter being provided with lateral slots 9 and a vent 10. Permanently in communication with the water reservoir 6, the float chamber is connected to a tube 12, the lower end of which is coupled to an electric throughflow heater 13 which, at choice, can be switched on fully or partly and communicates through a tube extending through the column 7 of the water reservoir with a swiveling horizontal tube 14, whose outlet 15 can be positioned centrally over the filter 4 or swung away out of this position.

Disposed in the float chamber 8 is a float 16 secured through a flexible tube 17 to a wall of the float chamber for free up-and-down movement between the bottom of the float chamber 8 and the hood 11. The float 16 contains a mercury switch 18, which is stationarily mounted therein, and whose contact points 19 and 20 are connected through leads 21 and

55

22, housed in the tube 17, to the throughflow heater 13 and to a source of electric current.

When the coffee-making apparatus is put into service, the tube 12 and the heater 13 should be filled with water to just below the float chamber 8. If, in that condition, in which the float 16 rests on the bottom of the float chamber 8, so that the heater 13 is in its switched-off position (FIG. 4), a given quantity of water is poured into the reservoir 6, a part of this water will immediately fill the float chamber 8. As a result, the float 16 will swing upwardly and the mercury 23 will be displaced to establish an electric connection between the contact points 19 and 20 (FIG. 3), which puts the heater 13 into operation. The water in the heater will be brought to the boil, forced upwardly, and passed through the outlet 15 to the filter 4, while 15 being replaced by water from the reservoir 6 and the float chamber 8. As soon as the supply of water is exhausted, so that the float chamber is empty, the float 16 will drop, whereby the displacement of the mercury 23 will break the electric connection between the contact points 19 and 20 and switch off 20 the heater 13.

The simple switch mechanism 16, 18 for controlling the heater can be made of sturdy construction so that it will be relatively invulnerable and operate reliably.

If so desired, the heater 13 may be arranged to operate at 25 full or half capacity, depending on whether the apparatus is used for the normal filtering method or for the quick-filtering method. For that purpose, a selection switch 24 can be included in the electric leads connected to the heater, by means of which the heater can be previously adjusted to operate at 30 full or half capacity after it has been switch on. Furthermore, a signal lamp 25 can be included in said electric leads to indicate that the heater is actually in its switched-on condition.

I claim:

1. A coffee-making apparatus comprising a hollow housing member, an electric throughflow heater located in said housing, a water reservoir supported on the upper end of said housing and having a bottom wall above said heater, a tube extending upwardly from said heater and centrally through said reservoir for connection to a horizontal tube having an outlet 40 to one side of said reservoir, said bottom wall having an opening therein, a float chamber below said opening and in communication with said reservoir, a connection from said float chamber to the bottom of said throughflow heater to pass water from said reservoir to said heater and out said tube to 45 said outlet, said float chamber having sidewalls connected to the bottom wall of said reservoir, a hollow float in said float chamber pivotally connected to a sidewall of said chamber by a flexible tubular sleeve fixed to said sidewall and opening through said sidewall, a mercury switch in said float positioned so that pivotal up-and-down movement of said float as said chamber is filled and emptied will close and open said switch, and lead wires passing through said tubular sleeve to said switch and connected to energize said heater when said switch is closed.
